UNITED STATES PATENT OFFICE.

WILLIAM H. BURSTALL, OF OXNARD, CALIFORNIA, ASSIGNOR OF ONE-HALF TO
WALTER ADAMSON, OF OXNARD, CALIFORNIA.

CIRCLE BRACE.

1,419,541.

Specification of Letters Patent. Patented June 13, 1922.

Application filed January 12, 1920. Serial No. 350,761.

To all whom it may concern:

Be it known that I, WILLIAM H. BURSTALL, a citizen of the United States, residing at Oxnard, in the county of Ventura and State of California, have invented a new and useful Circle Brace, of which the following is a specification.

My invention relates to a circle brace, which is the name given in the art, to an article used as a brace between the circular rack and the tool joint in a Barrett oil well jack.

An object of my invention is to provide a circle brace of the character referred to which will be readily adjustable, and which will incorporate a new and improved mode of adjustment.

A further object of my invention is to provide an adjustable circle brace, which will be sturdy and reliable in action, and simple and economical of manufacture.

Another object of my invention is to provide a circle brace with an improved device for application to a tool joint.

Other objects and advantages will appear in the subjoined detailed description.

Referring to the drawings:

Figure 1 is a perspective view illustrating my circle brace in operative position between a circular rack and tool joint in a Barrett oil well jack.

Fig. 2 is a longitudinal view partly in section of a preferred form of my invention.

Fig. 3 is a longitudinal view of the same looking from the right of Fig. 2.

Fig. 4 is a detail section of the means utilized for maintaining the same in adjusted position.

Fig. 5 is an end view of the same.

Fig. 6 is a section on a line indicated by x^6-x^6 in Fig. 4.

Fig. 7 is a section taken on a line indicated by x^7-x^7 in Fig. 4.

Fig. 8 is a longitudinal view of a section of the device illustrated in Fig. 2 with the hand wheel, serrated dog, and locking ring removed.

Fig. 9 is a perspective view of the locking ring employed in the preferred form of my invention illustrated in Fig. 2.

Fig. 10 is a perspective view of the hand wheel employed in the same.

Fig. 11 is a perspective view of the serrated dog employed in the same.

Referring to the drawings there is illustrated in Figure 1 a Barrett oil well jack. This device utilizes a circular steel rack indicated at 2, which rack is in practice secured to a derrick floor as indicated in Figure 1. A wrench post 3 is fixed at one end of the rack 2 and a traveling jack 4 is carried upon said rack 2.

The Barrett oil well jack is employed to set up or unscrew tool joints. As indicated in Fig. 1 a tool joint 5 is gripped by a pair of right and left wrenches 6 applied to opposite members of the joint. One of said wrenches 6 is fixed abutting the stationary wrench post 3. The other of said wrenches 6 abuts the traveling jack 4. Upon a movement of the jack 4 the wrenches 6 will set up or unscrew the joint 5.

It requires considerable power to set up or unscrew tool joints of the size for which is employed a Barrett oil well jack. In practice the setting up or unscrewing of the same produces a very considerable strain upon the wrenches 6 and upon the circular track 2. Considerable difficulty has been experienced by users of such type of jack because of the buckling of the rack 2 produced by the strain being applied to the rack at divergent points thereof.

My invention pertains to a device utilized to brace or translate a portion of said strain between the tool joint 5 and a point intermediate the wrench post 3 and the jack 4. This device comprises a brace 7 which engages at one end with the tool joint 5 and at the opposite end with the inner periphery of the rack 2. Such a brace will eliminate any buckling of the rack 2 by providing a direct reinforcement between the tool joints 5 and the rack 2 intermediate the wrench post 3 and jack 4.

Referring particularly to Figures 2-11 of the accompanying drawings the preferred form of my invention includes a barrel 8 which may be readily formed of a piece of heavy pipe. A plunger 9 is telescopically adjustable within the barrel 8. The plunger 9 is provided with a longitudinally extending series of serrations 10.

The barrel 8 is preferably enlarged at its plunger receiving end and is formed with an annular flange 11. Adjacent the flange 11 the barrel 8 is apertured as at 12 to receive a dog 13 which dog 13 is provided

with serrations 14 adapted to interfit with the serrations 10 of the plunger 9. The barrel 8 is threaded as at 15 adjacent the aperture 12 opposite the flange 11. The barrel 5 8 provides an annular seat 16 between the flange 11 and thread 15 upon which is rotatively mounted a ring like member 17. The ring like member 17 is provided on its inner periphery with a cam surface 18. A locking ring 19 is threaded upon the thread 15 to confine the ring longitudinally relative to the barrel 8. The barrel 8 is apertured to receive a pin 20 which is received within a longitudinal slot 21 formed in the 15 plunger 9.

10 The end 22 of the plunger 9 is flattened to engage within a slot formed on the inner periphery of the rack 2 of a Barrett oil well jack.

20 A slipholder 23 is swiveled upon the end 24 of the barrel. A pair of spaced slips 25 is rotatively mounted within the slipholder 23 transverse to the axis of the barrel 8.

25 The operation of the form of my invention last described is as follows: The brace is positioned with the flattened end 22 of the plunger 9 abutting the inner periphery of the rack 2 of a Barrett oil well jack and the slips 25 engage one member of a tool joint 30 5. The brace is so positioned by means of telescopically adjusting the plunger 9 within the barrel 8, which adjustment is accomplished by rotating the hand wheel 17 until the cam surface 18 releases the dog 13, 35 whereupon the plunger 9 is longitudinally movable relative to the barrel 8. When the desired adjustment of the plunger 9 and barrel 8 has been attained the hand wheel 17 is rotated or moved transversely of the barrel 40 8 until the cam surface 18 secures the serrations 14 of the dog 13 in engagement with the serrations 10 of the plunger 9, in which position the relative adjustment of the plunger 9 and barrel 8 will be maintained.

45 The slips 25 being spaced and serrated will engage with tool joints of varying diameters, and said slips being rotatively mounted within the slip holder 23 the brace

7 may be applied to the moving member of a tool joint.

50 My invention is not limited to any particular form or details of construction for in addition to the form above described there are a number of other forms of my invention, and my invention is of the full scope and breadth set forth in the following claims.

55 I claim:

1. A circle brace comprising telescopically adjustable sections, one of said sections having a longitudinally extending series of serrations, and means engaging said serrations to maintain said sections in adjusted relation, said means including a member movable in an arc relative to the longitudinal axes of said sections.

60 2. A circle brace comprising a barrel, a plunger telescopically adjustable within said barrel, said plunger having a longitudinally extending series of serrations, a dog carried by said barrel, said dog having serrations adapted to engage with said plunger serrations to maintain said barrel and plunger in adjusted relation, and means to secure said dog in engaging position.

65 3. A circle brace comprising a barrel, a plunger telescopically adjustable within said barrel, said plunger having a longitudinally extending series of serrations, a dog carried by said barrel having serrations adapted to engage said plunger serrations to maintain said barrel and plunger in adjusted relation, and a member carried by and surrounding said barrel, said member being provided with a cam surface to secure said dog in engaging position.

70 4. In combination with a circle brace, a slip holder swiveled upon one end of said circle brace, and a pair of serrated slips supported by said holder.

75 Signed at Oxnard, California, this 5th day of January, 1920.

WILLIAM H. BURSTALL.
